MECHANISM FOR PROPELLING VESSELS.

No. 373,492.

Patented Nov. 22, 1887.

UNITED STATES PATENT OFFICE.

THOMAS J. SIMPSON, OF WORTHINGTON, MINNESOTA.

MECHANISM FOR PROPELLING VESSELS.

SPECIFICATION forming part of Letters Patent No. 373,492, dated November 22, 1887.

Application filed April 13, 1887. Serial No. 234,719. (No model.)

To all whom it may concern:

Be it known that I, THOMAS J. SIMPSON, a citizen of the United States, residing at Worthington, in the county of Nobles and State of Minnesota, have invented certain new and useful Improvements in Mechanism for Propelling Vessels; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to propelling vessels; and its object is to provide mechanism which shall operate the propelling-wheels by means of wind-power. By this means I unite in one structure the advantages possessed by mechanically-driven vessels and those possessed by sailing-craft—that is to say, I dispense with complicated and costly sails and rigging, and also with the heat and smoke and expense of steam engines and boilers.

25 My invention consists, first, in the combination, with the wheel-shaft of a vessel, of a wind-wheel for actuating the same; secondly, in the combination, with the shaft of a screw-propeller, of a wind-wheel for turning it, and, 30 further, in various combinations and arrangements of parts, as hereinafter described, and particularly pointed out in the claims.

In the accompanying drawings, Figure 1 represents a longitudinal vertical section of a 35 vessel embodying my invention, and Fig. 2 is a side elevation of the same.

The same letters refer to corresponding parts in all the views.

A is the hull of the vessel, which is preferably constructed with overhanging bow and stern, as shown.

B is the shaft, which in this instance I have shown as provided with a screw-propeller, though it is obvious that my improvements 45 can be applied to paddle-wheel boats, either side-wheel or stern-wheel.

The shaft B preferably extends through both stem and stern of the vessel, and is provided at the bow with a screw-propelling wheel, C, 50 and at the stern with another screw, D. These screws may be of any preferred construction.

I have shown the forward screw, C, as a single tapering spiral blade, and screw D as a two-bladed double screw.

The shaft B is supported in the usual bearings, and passes through stuffing boxes at bow and stern. 55

Near one or both ends of the shaft B is secured a pair of bevel-wheels, E F, between which is a third bevel wheel or pinion, G, carried on the lower end of an upright shaft, H. The bevel-wheels E F are set far enough apart to allow but one of them to mesh with the bevel pinion G at the same time. In order to bring one or the other of these bevel-wheels 60 E F into engagement with the pinion G, the shaft B is arranged to slide longitudinally in its bearings. It passes through and turns freely in a toothed block or rack, I, which is fitted between collars fastened to the shaft, 65 and moves between suitable guides, K.

A lever, L, provided at its lower end with a toothed segment, l, meshing with the rack I, is pivoted in a standard, M, and is fitted with a latch, l', to engage with a notched quadrant, 75 L', which is fastened to the floor A', and so hold the lever in any desired position. By moving the lever forward or backward the shaft B will be shifted axially and one or the other of the gears E F brought into engagement with the bevel-pinion G. When the latch l' is placed in the central notch of the quadrant, neither of the gears E F will mesh with pinion G. Power to drive the shaft is communicated to it through these gears E, F, 80 and G; and for generating this power I employ a wind-wheel, N, preferably of the horizontal type and suitably mounted in bearings.

In the drawings I have shown such a wind-wheel as is described and claimed in my Patent 90 No. 325,366, dated September 1, 1885, to which reference may be had for a complete explanation thereof. It consists, in brief, of two or more shafts, N', passing through and revolving freely in a central bearing, N², and provided 95 at the ends with wind-sails N³, arranged at right angles to each other, as shown. As the wheel revolves, the sails on one side drop down and receive the force of the wind, while the sail on the opposite side is lifted to a horizontal position and offers but slight resistance to the air. The wheel therefore tends to re-

volve continuously in the same direction. This wind-wheel N may be mounted directly on the upper end of shaft H; but I prefer to place it on a counter-shaft, o, at the extreme 5 end of the vessel, in order to leave as much clear space as possible at the center of the vessel. Sprocket-wheels O' H' and a chain belt, P, communicate the power from the wind-wheel to the shaft H; or any other mode of 10 gearing may be used. I prefer to duplicate this mechanism, as shown in the drawings, and place a wind-wheel at each end of the boat. The construction is the same in both instances.

Q is the flanged steering-wheel, which is 15 connected by rope R, grooved wheel S', shaft s, wheel s², and chain T with the wheel U', which is keyed to the upper end of the rudder-post U. The rudder U' is cut away, as shown, to allow the sleeve V to encircle the 20 rudder-post, which turns freely therein. The sleeve V has formed on one side of it an out-board-bearing, W, for the end of the shaft B, said bearing being long enough to provide for the axial movement of the shaft. A set screw, 25 w, engaging with a wide groove around the shaft, prevents the latter from coming out of the bearing, as shown in Fig. 1 of the drawings, or without set-screw w, as shown in Fig. 2 of the drawings.

30 When the parts are in the position in which they are shown in Fig. 2, the vessel will be driven ahead. When it is desired to go astern, the lever L is thrown forward, which will draw the shaft B backward, and the gears E F will 35 mesh with bevel gear-wheel G and reverse the motion of the shaft B. Whether going ahead or astern, when the lever L is moved the pressure of the water against the screws C D will assist in shifting the shaft.

40 By the arrangement of the mechanism shown and described the heavy parts of the machinery are located below the water-line, and help to ballast the vessel, and it will also be observed that the deck-awning shown in Fig. 2 45 will assist in excluding a large portion of the sunshine and rain.

Having thus described my invention, what

I claim, and desire to secure by Letters Patent, is—

1. The combination, with a vessel, of a screw-shaft 50 capable of axial movement in its bearings, a pair of bevel gear-wheels secured on said shaft, a bevel-pinion located between the bevel-gears, a wind-wheel imparting motion to said bevel-pinion, and means for shifting the screw-shaft axially, so as to bring one or the other of the bevel-gears into engagement with the pinion, substantially as and for the purpose set forth.

2. The combination, with vessel A, of shaft 60 B, carrying screws C D and movable axially in its bearings, bevel-gears E F, keyed on said shaft, bevel-pinion G, mounted on shaft H, rack I, fitted between collars on the shaft B, toothed segment l, lever L, and wind-wheel N, 65 imparting motion to the shaft H, substantially as and for the purpose set forth.

3. The combination, with vessel A, of screw-shaft B, carrying screws C D and movable axially in its bearings, bevel-gears E F, secured on said shaft, pinion G, mounted on shaft H, wind-wheel N, mounted on shaft O, sprocket-wheels H' and O', mounted, respectively, on shafts H and O, chain P, connecting said sprocket-wheels, and suitable mechanism for shifting the shaft B axially, substantially as shown and described.

4. The combination, with vessel A, of screw-shaft B, rudder-post U, carrying rudder U' 80 and sprocket-wheel U', and having the sleeve V encircling it in a cut-away portion of the rudder, bearing W, secured to said sleeve and receiving the end of shaft B, flanged steering-wheel Q, shaft S, provided with grooved wheel S' and sprocket-wheel S², rope R, connecting 85 wheels Q and S', and chain T, connecting sprocket-wheels S² and U', substantially as and for the purpose set forth.

In testimony whereof I affix my signature in presence of two witnesses.

THOMAS J. SIMPSON.
